UNITED STATES PATENT OFFICE.

WILLIAM GRETHER, OF DAYTON, OHIO.

DESIGN FOR A PORTABLE ELECTRIC LANTERN.

52,237.

Specification for Design.

Patented July 30, 1918.

Application filed May 3, 1918. Serial No. 232,403. Term of patent 14 years.

To all whom it may concern:

Be it known that I, WILLIAM GRETHER, a citizen of the United States, residing at Dayton, in the county of Montgomery and State of Ohio, have invented a new, original, and ornamental Design for a Portable Electric Lantern, of which the following is a specification, reference being had to the accompanying drawing, forming part hereof.

Figure 1 is a front view of a portable elec-

tric lantern, showing my new design. And Fig. 2 is a side view thereof.

I claim:

The ornamental design for a portable electric lantern, as shown.

WILLIAM GRETHER.

Witnesses:

SAMUEL L. FINN,

HOWARD S. SMITH.
